DESIGN FOR A BOTTLE

Joseph H. R. Grant, Kew Gardens, N. Y.

Application November 3, 1933. Serial No. 49,643

Term of patent 14 years

To all whom it may concern:

Be it known that I, JOSEPH H. R. GRANT, a citizen of the United States, and a resident of Kew Gardens, borough of Queens, in the county of Queens, city and State of New York, have invented the new, original and ornamental Design for a Bottle, of which the following is a specification.

Reference is had to the accompanying drawing, forming part hereof, wherein

I claim:

The ornamental design for a bottle substantially as shown.

JOSEPH H. R. GRANT.
